GAS LIFT VALVE

William A. Dudley, Garland, Tex., assignor to Merla Tool Corporation, Dallas, Tex., a corporation of Texas
Filed Dec. 18, 1963, Ser. No. 331,576
5 Claims. (Cl. 137—155)

This invention relates to valves, and more particularly to gas lift valves of the pilot-operated type.

In pilot-operated gas lift valves a power piston is exposed to casing pressure on one side and selectively to casing and tubing pressure on the other side in response to opening and closing of a pilot valve. The position of the power piston will control the flow through the valve to provide a gas lift to the production tubing. During gas lift operations, casing pressure will exceed tubing pressure positioning the piston to allow gas flow through the valve into the tubing. When the tubing pressure exceeds casing pressure, it is generally desired that gas should not flow through the valve into the casing. To prevent such flow, reversal prior valves of this type have included a section between the outlet of the main valve and the tubing having a spring-loaded dart or back check valve. This included section complicates the valve structure and limits the valve to a larger size than would be necessary if the section could be omitted. Smallness of size and simplicity of structure are desirable features in a gas lift valve because of the limited space available in a well bore and the difficulty in servicing or adjusting a gas lift valve once it has been installed in a production well.

Therefore, an object of the present invention is to provide an improved pilot-operated gas lift valve having reduced size and a simplified structure.

Another object is to provide a pilot-operated gas lift valve including a reverse flow check incorporated in the main valve member.

A further object is to provide the main valve member of a pilot-operated gas lift valve with an annular slide ring assembly closing the valve when exposed to reverse pressure differentials.

Another object is to provide the main valve member of a pilot-operated gas lift valve with a ball check valve and a slide ring assembly to close the main valve when exposed to reverse pressure differentials.

Still another object is to provide structure in the main valve member of a pilot-operated gas lift valve preventing flow reversals.

A still further object is to provide a pilot-operated gas lift valve installed to conduct gas from a well casing to a production tubing having a back flow check valve in the main valve member wherein flow from the production tubing to the well casing is prevented.

Still another object is to provide a combined main valve member and back check flow valve in a pilot-operated gas lift valve.

Other objects, features and advantages of the invention will be apparent from the drawings, the specification and the claims.

In the drawings:

FIGURE 1 is a view partly in vertical section and partly in elevation showing a valve constructed in accordance with this invention, in operating position in a tubing string;

FIGURE 2 is a view partly in half-section and partly in quarter-section illustrating details of a preferred form of valve embodying this invention;

FIGURE 3 is a detail vertical sectional view of the main valve seat, the main valve member and the slide seal ring assembly of this invention, illustrating the opened position of the main valve member and the closed position of the slide seal ring assembly.

In FIGURE 3 the details of structure of the improve-

2

ment of this invention are clearly shown, and FIGURES 1 and 2 are included to illustrate a typical installation of a pilot-operated gas lift valve for conducting lift gas from a well casing to the production tubing and to illustrate the relationship of the improvement to a pilot-operated gas lift valve.

Referring to FIGURE 3, inlet thimble assembly 11 forms a part of the tubular housing 12 of gas lift valve V. Main valve seat 13 is provided by a downwardly and outwardly facing frusto-conical surface in the lower end of inlet thimble assembly 11. Main valve member 14 and sliding seal ring assembly 15 cooperate with valve seat 13 to control the flow of fluid through the valve.

The upper interior of main valve member 14 is bored and threaded to receive seat member 16 and depending hollow stem 17 of piston 18. The lower interior of main valve member 18 is bored as at 19 to receive ball check valve 20 between shoulders 21 and seat member 16 and has slots 22 extending into bore 19. With ball 20 seated on shoulders 21, a flow path for fluid flow will be available through the communication between slots 22 and bore 19 around ball 20. With ball 20 seated on seat member 16, such flow path through main valve member 14 will be blocked.

Sliding seal ring assembly 15 surrounds the upper portion of main valve member 14 and has interior surface 23 slidable on exterior surface 24 of main valve member 14. Groove 25 for O-ring 26 is positioned in surface 24 to provide a seal between surfaces 23 and 24. Main valve member 14 has outwardly and downwardly extending frusto-conical seating surface 27 which engages similar surface 28 on ring assembly 15 when main valve member is in seated position as shown in FIGURE 2.

Seal ring assembly 15 includes seal member 29 and retainer ring 30 and has downwardly and outwardly inclined frusto-conical seating surface 31. In closed position of assembly 15, seal member 29 will engage main valve seat 13, thereby shutting off the flow through main valve seat 13.

As can be seen from FIGURE 3, sliding seal ring assembly 15 is slidable on main valve member 14 and will close main valve seat 13 when exposed to reverse pressure differential, as hereinafter more fully explained.

FIGURE 1 illustrates the valve of this invention in position in the side pocket generally indicated as P of mandrel M forming a portion of the flow tubing T. In the form illustrated, the valve is designed for wireline operation. It will be apparent to those skilled in the art that, by changing the outlet sub 32 to the part commonly used with permanently installed valves, the valve could be secured to a lug on the exterior of a mandrel in the conventional manner. Of course, the side pocket packing would not be utilized, as it would serve no useful purpose.

Tubular housing 12 is provided by a number of housing parts for easy assembly. Beginning at the bottom of the valve, the lowermost part is the bottom sub or cap 32. Above the sub 32 is a packing adapter 33 which is connected to the lower end of the inlet thimble assembly 11. Above the thimble assembly 11 is the valve seat housing 34 which is connected to the lower end of spring housing 35. The upper end of the housing is completed by bellows adapter 36.

A fluid inlet is provided in the housing at 37 in inlet thimble assembly 11. Preferably, a number of inlet ports 37 are provided and this section of inlet thimble assembly 11 is surrounded by a screen 38 to screen out trash from the flow stream.

An outlet 39 is provided in bottom cap 32 and, as shown in FIGURE 1, communicates through port 40 with the interior of flow tubing provided by mandrel M. Inlet screen 38 is located with respect to side pocket P where it communicates with opening 41 so that the fluid from

the casing annulus may pass from opening 41 to the inlet 37 of the valve.

A flow passageway connects the inlet and outlet to convey fluid from the casing into the tubing mandrel M. This passageway is provided by a bore 42 in inlet thimble assembly 11, a bore 43 through lower packing adapter 33 and a bore 44 through bottom cap 32.

As previously described, valve seat 13 is provided in the interior of inlet thimble assembly 11 and cooperates with main valve member 14 in sliding seal ring assembly 15 to control the flow of fluid through the above-described flow passageway.

Control of main valve member 14 is provided by a power assembly. The power assembly is provided by a cylinder 45 in the valve seat housing 34 and piston 18 reciprocal in cylinder 45.

The cylinder 45 is exposed at its lower side to casing pressure through the bumper assembly indicated generally at 46. The upper end of cylinder 45 is closed providing a chamber 47 above the piston 18.

As hereinbefore mentioned, piston 18 is connected to main valve member 14 through stem 17 so that movement of the piston will effect movement of main valve member 14. It will be noted that the large end of piston 18 has a smaller diameter than the diameter of cylinder 45.

The piston assembly includes a piston 18 having a rigid frusto-conical periphery 49 with the small end 50 thereof facing main valve member 14.

The seal for the piston assembly is provided by an annular seal member 51 mounted on piston member 18. This seal member is preferably made from a material having a low co-efficient of friction which permits it to provide a seal of very light frictional forces. A material such as polytetrafluoroethylene, commonly known as "Teflon" may be used for this seal. Seal member 51 is formed with an inner frusto-conical wall 52 to conform to the outer periphery 49 of piston 18. Seal member 51 has an outer cylindrical wall 53 to conform to the wall of cylinder 45.

Preferably the angle of the frusto-conical wall 49 on piston member 18 is sufficient to be self-releasing from seal member 51 to avoid sticking of the seal member to the piston. It is also preferred that the outer diameter of seal member 51 be slightly larger than the diameter of cylinder 45 to give a slight pre-loading of the seal member against the cylinder.

Means are provided for urging seal member 51 upward toward the large end of piston member 18. A bumper washer 54 bears against the lower end of seal member 51 and spring 55 is held in compression between bumper washer 54 and an inwardly extending flange 56 within inlet thimble assembly 11. The force of spring 55 is sufficient to provide a slight plastic flow of seal member 51 to effect mating between seal member 51 and piston 18.

Bumper assembly 45 is positioned in the path of seal member 51 as it moves toward open position of main valve member 14. The bumper assembly is provided by bumper washer 54, a bumper member 57 and resilient means such as bumper rubber 58 supporting bumper member 57 in the path of bumper washer 54 as piston 18 moves toward open position of main valve 14. The upper end of bumper member 57 has a surface 59 adapted to engage the downwardly facing surface 60 of bumper washer 54 when piston 18 moves down. As these parts are engaged, the bumper rubber 58, which is confined between valve seat housing 34 and sleeve 61 depending from bumper member 57, is compressed. It will be noted that the confinement of the bumper rubber between the sleeve and housing is such as to permit it to move substantial distance in a radial dimension before completely filling the cavity between the sleeve and the housing. In this manner a substantial travel of the piston is permitted while the bumper assembly and the spring 55 build up resistance to downward movement of the piston. As soon as the bumper rubber 58 is completely compressed, down-

ward movement of the bumper member 57 is substantially arrested. By having this arresting movement transmitted from the bumper member through the bumper washer 54 to seal member 51, the frictional engagement of the seal with the cylinder is increased to thereby absorb a portion of the energy of the downwardly moving piston. It has been found that this arrangement of transmitting the impact force of the piston rubber will result in imbedding in the rubber of any particles which were too small to be wiped from the cylinder wall. This imbedding will minimize scoring of the cylinder wall.

The upper extremity of the cylinder wall is provided with an enlarged diameter section 62. This results in a shoulder 63 which acts as a wiper to wipe solid particles from the exterior seal member 51. The solid particles may be trash, or may be salts which tend to build up in some wells.

The piston 18 is constructed in a manner to direct any solid particles which appear in the chamber 47 above the piston on through the valve.

It is conventional in valves of the type illustrated to have a bleed port 64 which extends through the piston 18, stem 17 and main valve member 14 to place the upper end of cylinder 45 in communication with the passageway through the valve downstream of the main valve seat 13. In order to direct trash through this bleed passageway, the upper end of piston 18 is dished in, as shown at 65, so that any particles of trash falling on the top of the piston will tend to be directed to the bleed passageway.

To permit free passage of trash, the bleed passageway should be as large as possible. On the other hand, the size of this passageway controls the speed with which the piston will snap the main valve member to full open position. For this reason, the bleed passageway through piston 18 and stem 17 is made large and a depending member 66 extends into the inlet of the bleed passageway. The length of the member 66 is such that it will effectively reduce the size of the bleed passageway until the main valve member 14 is almost in fully open position. As the main valve member moves to fully open position, the piston 18 will move below the depending member 66 to clear the bleed passageway and open up the inlet to the bleed passageway to thus permit any trash to freely move into the bleed passageway and pass through the valve. It will be noted that there is a reduced diameter section 67 in passageway 64. This section is provided to control the flow through the passageway 64 without providing any extensive length of small flow area which could cause a blocking of the passageway with trash.

From the valve as thus far explained, it is apparent that the lower face of the control piston is always exposed to casing pressure and the upper face of the piston is always exposed to the pressure in the tubing. In accordance with conventional construction of valves of this type, a pilot valve indicated generally at 68 is provided for selectively admitting casing pressure to the closed end of cylinder 45 to thus selectively increase the pressure above the piston to casing pressure. An inlet into the pilot valve is provided by port 69 in valve seat housing 34. Valve seat 70 is supported on valve seat housing as shown and provides outlet ports 71 into chamber 47 above piston 18. The port 69 communicates with the spring housing 35 so that casing pressure will be applied to the bellows 72. Valve seat 70 is provided with O-ring seal 73 to prevent flow of casing pressure from port 69 into chamber 47 other than through valve seat 70. Pilot valve 68 is provided with a spherical plug 73 seating on valve seat 70 and valve stem 74. Means are provided for resiliently urging the valve stem toward seat 70. This means may include the spring 75 held under compression between jam nuts 76 on valve stem 74 and the lower extremity of upper bellows adapter 36. Also included in the means for resiliently urging the valve stem 74 towards the seat is the bellows 72 connected to the valve stem and exposed to the pressure fluid above seat 70.

In operation the valve V is run into the tubing which includes the mandrel M on a wire line. The wire line is attached to a wire line latch assembly, a portion of which is indicated generally at 77 in FIGURE 1. The valve is run into the side pocket P and landed in the position shown in FIGURE 1 in which the upper and lower spaced seals 78 and 79, respectively, will seal between the valve and the side pocket above port 69 and below port 37 on the valve and above and below inlet 41. Thereafter, the production fluids within the well may be lifted by gas introduced through the gas lift valve in the conventional manner. The pilot valve will be set to open at a selected casing pressure. Under normal operations casing pressure will be exerted against bellows 72 causing valve 68 to open allowing casing pressure into chamber 47 above piston 18 thereby causing downward movement of piston 18 opening main valve 14. When main valve 14 is open casing pressure enters through screen 38 and ports 37, flows through inlet thimble 11, bore 43 in packing adapter 33, bore 44 in outlet sub 32 and out through ports 39 and 40 into the tubing to provide a gas lift for the production within the tubing T.

When pilot valve 68 closes flow of fluid under casing pressure will be blocked and the pressure in chamber 47 will be dissipated through passageway 64 causing valve 14 to close.

If for any reason while valve 14 is open a sudden surge of pressure within tubing T increases the tubing pressure to a pressure above the casing pressure then such pressure reversal will cause sliding seal ring assembly 15 to close and ball check valve 22 will move upward into engagement with seat member 16 thereby blocking passageway 64 and causing main valve member 14 to move upwardly and close.

In certain instances in the production of fluid from a well the tubing pressure may gradually rise to be larger than the casing pressure. In such an instance as soon as the tubing pressure increases to a value greater than casing pressure, sliding seal ring assembly 15 will move upwardly to engage seat 13 on inlet thimble assembly 11 but ball check valve 20 will remain seated on shoulder 21 allowing the tubing pressure to be transmitted to the passageway 64 into chamber 47 within cylinder 45 above piston 18. This will cause piston 18 to remain in the downward position holding main valve member 14 open. However, in this position with sliding seal ring assembly 15 closed, no fluids will flow through valve seat 13, if tubing pressure builds up gradually to a pressure which is sufficiently high to open pilot valve 68 by exerting a pressure on spherical plug 73 through valve seat 70. The instant that spherical plug 73 raises off seat 70 there will be a flow through the passageway 64 which will cause ball check valve 20 to move upwardly into engagement with seat 16 thereby preventing further flow and causing valve member 14 to move upwardly into the closed position.

From this it can be seen that the main valve member of a pilot operated gas lift valve may be constructed in accordance with the present invention to provide a closing of the main valve member whenever the pressure downstream of the valve seat for the main valve member increases above the upstream pressure regardless of whether such excess pressure is rapidly or slowly built up. This is accomplished by the novel construction of the main valve member. By including such provision in the structure of the main valve member the overall size of the gas lift valve may be smaller than a gas lift valve having a separate back flow check valve.

The foregoing disclosure and description of the invention is illustrative and explanatory thereof, and various changes in the method, as well as in the details of the illustrated construction, may be made within the scope of the appended claims without departing from the spirit of the invention.

What is claimed is:

1. A gas lift valve, comprising a tubular housing, a main gas passageway through said housing, a valve seat surrounding said passageway, a pressure responsive power assembly mounted in said housing, a seal assembly adapted to engage said valve seat to control flow through said passageway, means slidably connecting said seal assembly to said power assembly to move said seal assembly into engagement with said valve seat, said seal assembly being free to move into engagement with said seat independent of said power assembly, a pilot gas passageway connecting to said power assembly, pilot valve means mounted in the housing and controlling flow through said pilot gas passageway, a bleed passageway connecting the main gas passageway downstream of said valve seat with said power assembly, and an excess flow valve mounted in said bleed passageway to prevent excess flow through said bleed passageway to said power assembly.
2. A gas lift valve according to claim 1 wherein said bleed passageway extends through said seal assembly and connecting means to said power assembly and said excess flow valve is mounted in the end of said bleed passageway in the main gas passageway.
3. A gas lift valve having a main valve member controlling flow through the valve, a piston member reciprocating in a cylinder for controlling opening and closing of the main valve in response to opening and closing of a pilot valve, and a bleed passageway extending through said piston and said main valve member, the improvement comprising an excess flow valve in said bleed passage, and said main valve member includes a sliding, seal ring assembly movable to coact with said piston member in controlling flow through the valve member in one direction, and responsive to pressure downstream to control flow through the valve independent of said piston member.
4. A gas lift valve comprising, a tubular housing, a main gas passageway through the housing, a main valve seat across said passageway, a cylinder in the housing having one end closed and one end exposed to the exterior of the housing, a piston member reciprocal in the cylinder, a valve member connected to said piston member and engageable with said valve seat for controlling flow through said passageway, a portion of said valve member movable independent of the movement of said piston member to engage said valve seat responsive to a build-up of pressure downstream of said valve seat in said main gas passageway higher than the pressure upstream of said main valve seat in said main gas passageway, a pilot gas passageway connecting the closed end of the cylinder with the exterior of the housing, a pilot valve means mounted in the housing in controlling flow through said pilot gas passageway, a bleed passageway connecting the closed end of the cylinder with the main gas passageway downstream of the main valve seat, and an excess of flow valve mounted in said bleed passageway to prevent excess flow through said bleed passageway to said closed end of said cylinder.
5. A gas lift valve according to claim 3 wherein said bleed passageway extends through said piston and said main valve member and extends in a generally vertical direction, and including

a valve seat defined in the lower end of said bleed passageway,
 a ball valve, and
 means securing the ball valve in the lower end of the
 passageway,
 said ball valve adapted to engage said seat in said bleed
 passageway when the flow through the bleed passageway to the closed end of said cylinder exceeds
 a predetermined rate of flow.
